UNITED STATES PATENT OFFICE.

SANFORD D. CASE AND LEVERETT E. CASE, OF RIDGEWOOD HEIGHTS, NEW YORK.

GRAVITY SASH-HOLDER.

No. 910,113.

Specification of Letters Patent.

Patented Jan. 19, 1909.

Application filed May 2, 1907. Serial No. 371,449.

To all whom it may concern:

Be it known that we, SANFORD D. CASE and LEVERETT E. CASE, citizens of the United States, residing at Ridgewood Heights, in the borough of Queens and State of New York, have invented a certain new and useful Improvement in Gravity Sash-Holders, of which the following is a specification.

This invention relates to sash holders and more particularly to frictional sash holders especially adapted to be used on railroad cars, the object being to provide a very simple, cheap and durable sash holder which can be readily secured in the ordinary window frame and one which will hold the sash in the desired position without any danger of its dropping by a sudden jar.

With these objects in view our invention consists in the novel features of construction, hereinafter fully described and pointed out in the claim.

In the drawing forming a part of the specification Figure 1 is a front elevational view of a window frame and sash partly broken away showing the holder in section. Fig. 2 is a detail vertical sectional view through our improved holder arranged in the frame. Fig. 3 is a front view of the holder detached.

30 In the drawing A indicates an ordinary car window frame, B the sash and C our improved holder.

The stiles of the frame are provided with slots in which are secured the holders C, the description of one being sufficient for both as they are formed exactly alike.

The holder comprises a rectangular casing C' provided with flanged ends C², which fit in recesses formed in the frames above and below the slots. Secured over the casing and flanged ends is a slotted plate D which closes the casing and is secured in place by screws passing into the frame, through openings formed in the plate adjacent each end and the openings of the flanges of the casing. The sides of the casing are slotted as shown at C³ in which are mounted the stud pins E' of a metal roller E which is normally held in the slot of the plate against the edge of the sash forming a bearing roller for the sash when being raised.

Extending transversely through the casing is a shaft F on which is mounted the

central apertured rib G' of a plate G which is held into engagement with the roller by a coiled spring H, one end of which is secured over a pin G² secured to the upper end of the plate and the other end over a pin D' secured in the plate D. The bottom of the casing is provided with a shoulder C⁴ forming a stop for the plate G, which prevents the roller from riding too far up on the plate when the sash is raised. 55 60

The operation is as follows: As the sash is lifted the roller rotates forming roller bearings for the sash, as it is raised at the same time the rollers ride up on the plate forcing the lower ends of the plates forward until they strike the shoulders of the casing and in this position the rollers will 65 70 75 rotate freely as the sash is pushed up. When the sash is released the rollers will rotate in a reverse direction and start downwardly until they wedge between the plate and sash which will hold the sash securely raised without any danger of it dropping by a sudden jar. As the sash is pulled farther down the rollers will be forced over the center of the plates and the frictional contact of the plates against the rollers will 80 85 90 95 form a brake for the same and prevent the rollers from rotating so that the sash will be held in the position desired.

What we claim is:—

A sash holder of the kind described comprising a casing provided with vertical slots in its sides adapted to be arranged in a window frame, said casing being provided with a shoulder in its bottom, a slotted plate arranged over said casing, a shaft extending transversely through said casing, a plate provided with a central apertured rib mounted on said shaft, a pin extending outwardly from the upper end of said plate, a pin extending from the slotted plate, a coiled spring connected to said pin, for holding said plate against the shoulder of the casing, and a roller mounted in the casing provided with stud pins extending out through the vertical slots, for the purpose described. 85 90 95
